UNITED STATES PATENT OFFICE.

WILLIAM F. McNABB, OF PITTSBURGH, PENNSYLVANIA

HEAT-PRODUCING COMPOUND.

1,143,295.

Specification of Letters Patent. Patented June 15, 1915.

No Drawing.

Application filed October 23, 1914. Serial No. 868,291.

To all whom it may concern:

Be it known that I, WILLIAM F. McNABB, a resident of Pittsburgh, in the county of Allegheny and State of Pennsylvania, have 5 invented a new and useful Improvement in Heat-Producing Compounds, of which the following is a specification.

This invention relates to heat producing compounds or mixtures, and particularly for 10 use in cleaning drainage or sewer pipes or conduits, closet bowls or basins, for removing residual obstructions from oil or gas wells, for attacking oils or greases, as a 15 source of heat for food products, or as a disinfecter or deodorizer.

The object of the invention is to provide a compound or mixture of the kind described which can be manufactured at low cost, which is stable under normal conditions, which produces heat without flame 20 when mixed with water, and also produces no malodorous, combustible or explosive gases and may therefore be safely used under any conditions, and which also has a 25 strong solvent effect so that it will quickly remove obstructions from pipes or conduits.

The invention comprises the compound or mixture hereinafter described and claimed.

The composition and proportions of the 30 various substances in the compound may be varied within certain limits. In its simplest form it consists of a combination of an alkaline substance, such as sodium or potassium hydrate, in solid form, combined 35 with one or more oxidizing agents, such, for example, as oxalic acid or a persulfate, or both. The alkaline substance in solid form produces large quantities of heat when mixed with water and also produces a strong 40 alkaline solution which will readily dissolve a large variety of substances. The oxalic acid and persulfate probably act as oxidizing agents, especially in the presence of the hydrate, to consume portions of the obstructing material.

In the preferred form of the mixture sodium hydrate and potassium persulfate are used, although of course it is to be understood that potassium hydrate and per- 50 sulfate of either sodium or ammonium are also suitable.

One mixture which has given satisfactory results has the following formula:

55 Sodium hydroxid..... 15 grams.
Oxalic acid crystals..... 5 grams.
Potassium persulfate ($K_2S_2O_8$)..... 5 grams.

The compound is used by mixing it with

a quantity of water, say, 1 oz., the mixture being then poured into the pipe or conduit from which it is desired to remove an obstruction. The composition just described is found to generate a temperature of about 225° F., and the solution is active for about three minutes. This solution dissolves bristles, hair, paper, rags and leather, leaving no solid residue and producing no gases of any kind. If desired, a more violent and effective action can be secured by adding to the mixture a quantity of metallic aluminum, preferably in some finely divided form, such as shavings or the granulated metal. This aluminum combines with the hydrate to form an aluminate, giving off hydrogen, which in the nascent form is taken up by the oxidizing agents present, so that no free inflammable or explosive gas is produced when the composition is added to water. The proportion of aluminum may vary, but in the composition above described about $\frac{1}{2}$ gram of the metal is used. A mixture of 80 this kind generates a temperature of about 250° F., and is active for a considerable period, say 15 minutes or so. The mixture may also be improved by the use of other or additional oxidizing agents, such as the 85 nitrates, of which potassium nitrate is a fair example, or tartaric acid, and like substances. If potassium nitrate is used $\frac{1}{2}$ gram in either of the mixtures above referred to is found to improve the results, while 3 90 grams of tartaric acid produces very satisfactory results.

The mixture attacks and dissolves almost all forms of solid matter such as are commonly found in drainage and sewer pipes, or residual obstructions in oil and gas wells. It does not attack porcelain, lead, steel, iron, brass, or enamel ware, and can be safely handled under almost all conditions. It can be put up in packages of convenient form 95 with all the necessary substances mixed in the proper proportions ready to be added to the proper quantity of water. It can be used by mixing it with the water and pouring it down the drain pipe, or by applying the dry mixture to the place where it is to be used and then pouring the water over it.

The composition may be put up in packages containing any desired quantity, and preferably is put up in sealed form, for example, in an air-tight tin can, so that the substances will not deteriorate. It can be used in various ways and for various purposes. One important use is for producing

heat in the preparation of food products. In this case the tin can or container will be provided with say two compartments, one for containing the food, such as baked beans, or the like, and the other for containing the proper charge of the heat producing compound. The water may then be placed directly in the compartment containing the compound for producing heat for warming up the food, or the compound may be placed in a separate receptacle and water added thereto, and the receptacle containing the food products placed in the solution. This arrangement is particularly suitable for soldiers' rations or for camp use, as it provides a convenient package of food and the essentials for heating the same. The compound or mixture may also be used in disinfecting or deodorizing. In the forms above described it of course is a disinfecter in that the heat produced is itself sufficient to destroy many different kinds of germs. However, to increase the disinfecting efficiency a suitable quantity of disinfecting material may be added to the compound. Preferably, some material which has a solid form, such as bichlorid of mercury. 3/10 of a gram of this material in the mixture as above described is found to produce satisfactory results, although any suitable amount may be used and other solid disinfectors are suitable. Also, any substance which produces a pleasing odor may be added to the compound if desired. Preferably, substances will be used having a solid form and which give off a pleasing odor when dissolved in water, or the like. Such substances, for example, are vanillin, musk, or camphor products.

40 What I claim is:—

1. A heat producing compound or mixture, containing a solid hydrate, a persulfate, and oxalic acid.
2. A heat producing compound or mixture, containing sodium hydrate, a persulfate, and oxalic acid.
3. A heat producing compound or mixture, containing sodium hydrate, potassium persulfate, and oxalic acid.
4. A heat producing compound or mixture, containing substantially three parts sodium hydrate and one part each of potassium persulfate and oxalic acid.
5. A heat producing compound or mixture, containing a solid hydrate, a persulfate, oxalic acid, and aluminum.
6. A heat producing compound or mixture, containing sodium hydrate, a persulfate, oxalic acid, and aluminum.
7. A heat producing compound or mix-

ture, containing sodium hydrate, potassium persulfate, oxalic acid, and aluminum.

8. A heat producing compound or mixture, containing a hydrate, a persulfate, a nitrate, and oxalic acid.

9. A heat producing compound or mixture, containing sodium hydrate, a persulfate, a nitrate, and oxalic acid.

10. A heat producing compound or mixture, containing sodium hydrate, potassium persulfate, potassium nitrate, and oxalic acid.

11. A heat producing compound or mixture, containing a hydrate, a persulfate, a nitrate, oxalic acid, and aluminum.

12. A heat producing compound or mixture, containing sodium hydrate, a persulfate, a nitrate, oxalic acid, and aluminum.

13. A heat producing compound or mixture, containing sodium hydrate, potassium persulfate, potassium nitrate, oxalic acid, and aluminum.

14. A heat producing compound or mixture, containing a hydrate, a persulfate, a nitrate, oxalic acid, and tartaric acid.

15. A heat producing compound or mixture, containing sodium hydrate, a persulfate, a nitrate, oxalic acid, and tartaric acid.

16. A heat producing compound or mixture, containing sodium hydrate, potassium persulfate, potassium nitrate, oxalic acid, and tartaric acid.

17. A heat producing compound or mixture, containing a hydrate, a persulfate, a nitrate, oxalic acid, aluminum, and tartaric acid.

18. A heat producing compound or mixture, containing sodium hydrate, a persulfate, a nitrate, oxalic acid, aluminum, and tartaric acid.

19. A heat producing compound or mixture, containing sodium hydrate, potassium persulfate, potassium nitrate, oxalic acid, aluminum, and tartaric acid.

20. A heat producing compound or mixture, containing substances in substantially the proportions:

Sodium hydrate	15 grams.
Oxalic acid	5 grams.
Tartaric acid	3 grams.
Potassium persulfate	5 grams.
Aluminum	1/2 gram.
Potassium nitrate	1/2 gram.

In testimony whereof, I have hereunto set my hand.

WILLIAM F. McNABB.
